[57] CLAIM

The ornamental design for a bottle, substantially as shown and described.

DESCRIPTION

FIG. 1 is a front elevational view of a bottle showing my new design, the opposite side being a mirror image of the side shown;

FIG. 2 is an elevational view taken from the right of FIG. 1, the opposite side being a mirror image of the side shown;

FIG. 3 is a top plan view thereof;

FIG. 4 is a sectional view taken through lines 4-4 of FIG. 1; and

FIG. 5 is a sectional view taken through lines 5-5 of FIG. 1.

FIG. 1

FIG. 2

FIG. 3

FIG. 4

FIG. 5

UNITED STATES PATENT AND TRADEMARK OFFICE
CERTIFICATE OF CORRECTION

PATENT NO. : DES. 243,659
DATED : March 15, 1977
INVENTOR(S) : James E. Plummer

It is certified that error appears in the above-identified patent and that said Letters Patent are hereby corrected as shown below:

On page 1 of the specification before the first paragraph insert -- This is a continuation-in-part application of application D-601,952 filed August 4, 1975, which latter application is now abandoned. --

Signed and Sealed this

Twenty-eighth Day of June 1977
